UNITED STATES PATENT OFFICE.

RALPH L. QUASS, OF HAWTHORNE, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed October 26, 1927. Serial No. 228,710.

This invention relates to telephone systems and particularly to improvements in trunking circuits.

The object is to simplify the equipment 5 and to increase the reliability of operation in a toll trunking system serving coin lines.

In the past it has been the practice for the toll operator to collect, by means of a key, the coin deposited by the calling subscriber 10 in his coin box to enable him to dial for the toll connection.

According to the present invention, this system has been simplified and rendered more reliable by eliminating the manual collection 15 of the coin and providing a means responsive when the toll operator answers a call over a trunk, for automatically refunding the coin. This means may consist of an interrupter, and a relay control arrangement operated when 20 the toll operator answers the call for applying an impulse of, for example, 110 volt negative direct current from the trunk over the tip and ring conductors of the established connection to the calling subscriber's station 25 for the operation of the coin box magnet to refund the coin. This impulse may be applied for example, for a period of one-half of a second to insure the proper response of the coin box magnet.

30 The invention has been illustrated in the accompanying drawings in which Fig. 1 shows a trunk at an automatic office arranged in accordance with this invention, a coin box subscriber's station, and intervening automatic switches in diagrammatic form for seizing the trunk; Fig. 2 shows the incoming end of this trunk terminating in a jack at a toll operator's position. A portion of a toll operator's cord is also shown in this figure. Fig. 40 3 shows a modified arrangement of the invention in which certain portions of the equipment are common to a plurality of trunk circuits.

A description will first be made of the functions of the circuit arrangement shown in 45 Figs. 1 and 2 followed by a description of the modified arrangement shown in Fig. 3. A call may be established from the calling coin box subscriber's station A through switches 50 at an automatic office B and trunk T to the toll operator's position C, and similarly from the calling coin box subscriber's station D through switches at an automatic office E and the modified trunk F to the toll operator's position C. It should be understood

that only the outgoing end of the trunk F is modified and that the incoming end is identical for both trunks. As the apparatus in the machine switching offices whereby calling subscribers may seize these trunks forms no 60 part of the invention, none of this apparatus has been illustrated, except to indicate the brushes of line finders LF and LF' and selector switches S and S'. Switches S and S' may be operated to seize the terminals of 65 trunks T and F respectively. None of the apparatus at the toll operator's position C has been shown, except the answering plug of an ordinary cord circuit, as this equipment forms no part of the invention and is not essential 70 for the description thereof.

Assuming then that the subscriber at station A has deposited a coin to close a connection to ground for the coin box magnet 34 to enable him to operate dial 35; that he 75 has dialed a certain code number to secure a connection to a toll operator and that the brushes of switch S have just seized the terminals 2 of the trunk T, the first effect of this seizure will, as is well known in the art, 80 be the energization of relay 4. The circuit for this relay may be traced from battery, winding of relay 4, lower left hand winding of repeating coil 5, lower outer armature and back contact of relay 6, lower make-before- 85 break contacts of relay 7, ring terminal of the group of terminals 2 and the corresponding brushes of switches S and LF through the subscriber's loop back over the tip brushes of switches S and LF, tip terminal of the 90 group 2, upper outer armatures and back contacts of relays 7 and 6, upper left hand winding of repeating coil 5 to ground at the inner right hand armature and back contact of relay 8. The operation of relay 4 closes 95 an obvious circuit for the operation of relay 10 to close a circuit for relay 11 as follows: battery, winding of relay 11, right hand armature and back contact of relay 12, lower inner armature and front contact of 100 relay 10 to ground. Relay 11 in operating closes a circuit from ground through the left hand windings of repeating coil 14 to the sleeve terminal of the group 2 to hold the preceding selector in actuated position. 105

The operation of relay 11 also closes an obvious circuit for the operation of relay 16. This relay in operating closes a circuit for the transmission of a ringing tone for the calling subscriber from source 17 over a 110

- circuit as follows: tone source 17, outer right hand armature and back contact of relay 18, condenser 19, outer left hand armature and front contact of relay 16 to the ring conductor of the trunk through the subscriber's line loop and back to the tip conductor to ground at the inner right hand armature and back contact of relay 8. This tone indicates to the calling subscriber that the toll operator 5 is being signalled.
- Relay 16 connects at its right hand armature and inner left hand armature and front contacts, ground and battery through the windings of relay 12 and the right hand 10 windings of repeating coil 5 through upper armature and lower outer armature and front contacts of relay 10 to the tip and ring conductors of trunk T through the winding of the polarized relay 101 and the high resistance 15 102. This circuit causes the operation of the polarized relay 101 which in turn closes an obvious circuit for the operation of relay 103. This relay in operating its lower armature closes a circuit for the lighting 20 of lamp 104; this circuit being completed through the left hand armature and back contact of relay 105. Lamp 104 lights to indicate to the toll operator that a connection 25 is desired over this trunk.
- The toll operator answers this call by inserting the plug 107 of an ordinary standard toll cord into jack 108. A circuit is 30 thereby established over the sleeve terminals of plug 107 and jack 108 for the operation of relay 105. Relay 105 in operating opens the circuit for lamp 104 which is thereby extinguished. Relay 105 also closes an obvious circuit for the operation of relay 110. This relay closes at its armature and front 35 contact a low resistance bridge across the tip and ring conductors of trunk T by shunting the high resistance 102. Due to this low resistance bridge relay 12 will now operate to close a circuit for slow releasing relay 40 120 as follows: battery, winding of relay 20, outer left hand armature and front contact of relay 12 to ground at the armature and front contact of relay 11. Relay 20 closes a circuit for the operation of relay 18 as 45 follows: battery, right hand winding of relay 18, armature and front contact of relay 20, left hand armature and back contact of relay 22, inner left hand armature and front contact of relay 12 to ground. Relay 18 in 50 operating provides a locking circuit for itself, as follows: battery, left hand winding of relay 18, inner left hand armature and front contact of this relay, make-before-break contacts of relay 23, armature and front contact of relay 11 to ground. Relay 18 by opening the connection at its outer right hand armature and back contact removes the tone for the calling subscriber supplied from the tone source 17. This relay 55 also provides a holding circuit for relay 11

by establishing a connection to ground through its inner right hand armature and front contact. This is for the purpose of holding this relay operated and the preceding switches busy as long as the toll operator's cord is connected to the trunk. 70

Relay 18 in operating closes a circuit for the operation of relay 8 as follows: battery, winding of relay 8, outer right hand armature and back contact of relay 23, outer left 75 hand armature and front contact of relay 18 to ground. Relay 8 in operating closes an obvious circuit for the operation of relay 7. This relay in operating closes a locking circuit for itself through its winding, and inner 80 lower armature and front contact to ground at the armature and front contact of relay 11. Relay 8 in operating removes the direct connection to ground at its inner right hand armature and back contact for the tip conductor of the trunk through the upper left hand winding of repeating coil 5 to the calling subscriber's line and a connection from the tip conductor will now pass through resistance 25 to ground. This is to reduce the 85 amount of click to the calling subscriber when relay 7 operates to reverse battery. Relay 7 in operating reverses the connections from battery through the winding of 90 relay 4 and from ground through the resistance 25 for the subscriber's lines to effect certain operations in the switches between the calling subscriber and the trunk which are of no importance in connection with this invention and need not be described here. 95

The operation of the relays 8 and 7 closes circuits for the automatic return of the coin deposited by the subscriber to enable him to call. If the interrupter 27 is closed to ground at the time of the operation of these relays, 100 relay 28 will be operated over a circuit as follows: From battery, through resistance 29, left hand armature and front contact of relay 8, winding of relay 28 to interrupter 27 to ground. Relay 28 in operating closes a 105 shunting circuit for relay 30 so that this relay cannot operate at this time. This shunting circuit may be traced from battery through resistance 31, front contacts of the inner upper armature of relay 7, outer left hand armature and back contact of relay 23, right hand armature and front contact of relay 28 to ground. The circuit for relay 30 that is shunted by the above mentioned circuit may be traced from battery through the resistance 110 31, inner upper armature and front contacts of relay 7, winding of relay 30 to ground at the outer left hand armature and front contact of relay 18. The interrupter 27 may be arranged so that it will close a connection to 115 ground every other half second and maintain it closed for one-half of a second each period. 120

On the first opening of a connection to ground by the interrupter after the operation of relays 8 and 7, the shunting circuit for 125 130

relay 30 is opened due to the release of relay 28 and relay 30 operates. The operation of relay 30 closes a circuit for relay 32 as follows: battery, left hand winding of relay 32, right hand armature and front contact of relay 30, inner left hand armature and back contact of relay 33, make-before-break contacts of relay 23 to ground at the armature and front contact of relay 11. Relay 32 in operating provides a locking circuit for itself as follows: from battery through the right hand armature and front contact of relay 32 and its right hand winding to ground at the outer left hand armature and front contact 15 of relay 18.

On the next closure of the connection from ground through interrupter 27 and operation of relay 28 the shunting circuit for relay 30 is closed so that this relay will now release.

20 In releasing a circuit is closed for the operation of relay 33 as follows: battery, winding of relay 33, inner left hand armature and front contact of relay 32, left hand armature and back contact of relay 30 to ground at the outer left hand armature and front contact of relay 18. Relay 33 provides a locking circuit for itself from battery through its winding, inner right hand armature and front contact to ground at the armature and front contact of relay 11. 25 Relay 33 in operating closes a circuit for the operation of relay 6 from battery through the winding of this relay, outer right hand armature and front contact of relay 33 to ground. Relay 6 in operating opens the connection to battery and ground from the calling subscriber's line and thus causes the release of relay 4 but relay 10 is maintained 30 operated by the ground supply at the lower inner armature and front contact of relay 6. A connection is now established from a 110 volt negative current source through the outer left-hand armature and front contact 35 of relay 32 and the outer upper and lower armatures and front contacts of relay 6 to the tip and ring conductors leading to the calling subscriber's line. Current from this source will now operate the coin box magnet 34 at the subscriber's station to refund the coin which he had deposited to enable him to dial. The coin magnet 34 finds a discharge surge path to ground through the resistance and condenser unit 36 to ground at the middle 40 right hand armature and front contact of relay 33. This current from the 110 volt negative source is applied to the coin magnet 34 for one-half of a second, that is, as long as relay 30 remains released.

45 This period is sufficient to permit the coin magnet 34 to operate and refund the coin. When the connection from ground through the interrupter 27 is removed and relay 28 releases relay 30 is again operated and at 50 this time the locking circuit for relay 32 is

shunted to cause this relay to release. The shunting circuit may be traced from battery through the inner right hand armature and front contact of relay 33, left hand armature and front contact of relay 30, to ground 70 at the outer left hand armature and front contact of relay 18. When relay 32 therefore releases the connection from the 110 volt negative current source is opened at the outer left armature and front contact of this relay 75 and the coin magnet 34 is released.

When the ground is again applied through interrupter 27 relay 28 is operated and relay 30 is released, and relay 23 is operated over a circuit as follows: from battery through 80

the winding of relay 23, outer left hand armature and front contact of relay 33, inner left hand armature and back contact of relay 32, left hand armature and back contact of relay 30 to ground at the outer left hand armature and back contact of relay 18. Relay 23 provides a locking circuit for itself from battery through its winding, inner right hand armature and front contact to ground at the armature and front contact of relay 11. 90

The operation of relay 23 opens the shunting circuit for relay 30 at its outer left hand armature and back contact and opens at its make-before-break contacts the locking circuit for relay 33 which is now released.

It also opens the circuit for relay 8 at its outer right hand armature and back contact so that this relay will also release and establish a connection to ground for the tip conductor of the trunk, in place of the 100 connection through resistance 25. The purpose of this direct connection to ground is of no importance in connection with this invention and need not therefore be further described.

The operation of relay 23 also 105 opens the locking circuit for relay 18 at the make-before-break contacts but relay 18 is maintained operated through its original energizing circuit under control of relay 12 as hereinbefore described.

110 This trunk is also arranged to pass so-called class of service tones to the toll operator. These tones may be applied on the sleeve conductor of the selector S through the left hand windings of repeating coil 14 115 which are connected to ground at the armature and front contact of relay 11. When, now, relay 23 operates as described above, the right hand windings of repeating coil 14 are connected across the tip and ring conductors of the trunk T. The circuit for these windings may be traced from the tip conductor of the trunk T through the outer right hand armature and back contact of relay 22, 120 right hand windings and the intervening condenser of repeating coil 14, inner left hand armature and front contact of relay 23, inner right hand armature and back contact of relay 22 to the ring conductor of 125 trunk T. The class of service tones are 130

135

therefore repeated through coil 14, to the toll operator's cord connected to jack 108. The toll operator may remove the class of service tone from the trunk by operating the tone removal key 111. The operation of this key closes an obvious circuit for the operation of relay 112 and this relay in operating places a short-circuit for the high resistance 102 in the bridge across the tip and ring conductors. Relay 112 in operating also opens the circuit for the release of relay 110. Relay 110 in releasing opens the original short-circuit for resistance 102; the short circuit now being maintained by relay 112. On the release of key 111 relay 112 is released to open the short circuit across the resistance 102 and again closes the circuit for the operation of relay 110. Relay 110 is slow in operating so that the short circuit across resistance 102 will be delayed for the period it takes this relay to operate. Hence the resistance 102 will be bridged across the tip and ring conductor for a short period due to the operation and release of key 111. This temporary application of a high resistance bridge across the tip and ring conductors causes a momentary release of relay 12. Relay 12 in releasing removes the shunt circuit for relay 22 established at the inner left hand armature and front contact of relay 12 so that relay 22 will now operate in series with the relay 18 in a circuit, from battery through the right hand winding of relay 18, armature and front contact of relay 20, winding of relay 22 to ground at the armature and front contact of relay 11. Relay 20 is slow in releasing so that it will be maintained operated during the release of relay 12 and consequently relays 18 and 22 will be maintained operated through the circuit at its armature and front contact. When relay 12 is again operated the circuit for relay 20 is reestablished at the outer left hand armature and front contact. The operation of relay 22 opens the circuit from the right hand windings of repeating coil 14 across the tip and ring conductors of trunk T and thus the class of service tone is removed from the trunk. The operation of relay 22 and the operation of relay 12 closes a connection direct to ground for the sleeve and thereby shunts the primary windings of repeating coil 14 which as noted are connected to ground at the armature and front contact of relay 11.

A connection between the calling subscriber and the toll operator is now completed, with the talking battery and ground now supplied for the calling subscriber through the winding of relay 4 and at the inner right hand armature and back contact of relay 8. The calling subscriber may now give the number of the wanted subscriber to the toll operator and as is well known in the art, the toll operator may es-

tablish the connection to the wanted subscriber. Conversation between the calling subscriber and the called subscriber may then begin as soon as the calling subscriber has deposited the required coins in payment for the call.

The toll operator instructs the calling subscriber to deposit the proper amount and arrangements are made in the usual manner for refunding or collecting the deposited coins. The usual procedure would be for the toll operator to dial the trunk T over which this connection has been completed and control through suitable means such contacts as 38, 39 and 40. This arrangement forms no part of this invention and will not be further described except to say that the contact 38 may be controlled to close a connection to ground for the operation of relay 41. Relay 41 in operating closes an obvious circuit for the operation of relay 6. The contacts 40 are now actuated towards the left or right to apply either 110 volt negative or positive current to the tip and ring conductors leading to the calling subscriber to operate the coin magnet 34. If 110 volt negative current is applied, the coins are refunded, while the application of 110 volt positive current is for the purpose of collecting the coins. Contact 37 is also operated to transmit a low or high tone over the tip conductor to the toll operator through conductor 42 and upper inner armature and front contact of relay 6, to indicate that the refunding or collecting of the coins has been successfully performed. When the contact 38 opens the circuit for relay 41 this relay and relay 6 release and as both of these relays are slow in releasing sufficient time is provided for the coin magnet 34 to function.

If supervision is desired from the calling subscriber the manipulation of his switchhook will alternately cause the release and operation of relay 4. Relay 4 in releasing releases relay 10. Relay 10 in releasing reverses the battery and ground connection through relay 12 for the tip and ring conductors of trunk T and the polarized relay 101 is thereby released to cause the release of relay 103. Relay 103 applies battery and ground through its armatures and back contacts to the tip and ring conductors leading to the toll operator's cord and thereby cause the supervisory lamp in this cord to be correspondingly actuated as is well known in the art.

The connection is held established as long as relay 12 is maintained operated. When the calling subscriber releases relay 4 by hanging up his receiver, relay 10 is released to cause the release of relays 101 and 103 to signal the toll operator that a disconnection is desired. When the toll operator now removes the toll cord plug 107 from jack 108 relay 105 is released causing the release of

relay 110 so that the high resistance 102 is then bridged across the tip and ring conductors of trunk T causing the release of relay 12. Relay 12 in releasing causes the release 5 of relay 20. Relay 20 in releasing causes release of relay 18 and relay 22. Relay 18 in releasing causes the release of relay 11. Relay 11 in releasing causes the release of relays 23, 7 and 30 and ground is removed 10 from the sleeve conductor so that the preceding switches are restored to normal.

If it is now assumed that the subscriber at station D has deposited a coin to close a connection to ground for the coin box 234 to 15 enable him to operate dial 235; that he has dialed a certain code number to secure a connection to a toll operator and that the brushes of switch S' have seized the terminals 202 of trunk F, the first effect of this seizure will be 20 the energization of relay 204. The circuit for this relay may be traced from battery, winding of relay 204, lower left hand winding of repeating coil 205, lower outer armature and back contact of relay 206, ring terminal 25 of the group of terminals 202 and the corresponding brushes of switches S' and LF', through the subscriber's loop, back over the tip brushes of switches LF' and S', tip terminal of the group 202, upper outer armature and back contact of relay 206, upper 30 left hand winding of repeating coil 205 to ground. The operation of relay 204 closes an obvious circuit for relay 210 which in turn closes a circuit for the operation of relay 35 211 as follows: battery, winding of relay 211, right hand armature and back contact of relay 212, inner lower armature and front contact 210 to ground. Relay 211 in operating closes the circuit from ground for the left 40 hand windings of repeating coil 214 to the sleeve terminal of the group 202 to hold the selector S' in actuated position.

The operation of relay 211 also closes an obvious circuit for the operation of relay 45 216. This relay in operating closes a circuit for the transmission of ringing tone to the calling subscriber as follows: tone source 217, outer right hand armature and back contact of relay 218, condenser 219, outer left 50 hand armature and front contact of relay 216, the ring conductor of the trunk through the subscriber's line loop, to the tip conductor to ground at the upper left hand winding of repeating coil 205. This tone indicates to 55 the calling subscriber that the toll operator has been signalled.

Relay 216 in operating connects at its right hand armature an inner left hand armature and front contacts, ground and battery from 60 the windings of relay 212, through the right hand windings of repeating coil 205, upper armature and lower outer armature and front contacts of relay 210, the tip and ring conductors of trunk F, the winding of the polarized 65 relay 101 and the high resistance 102. This

circuit causes the operation of the polarized relay 101 which in turn closes an obvious circuit for the operation of relay 103. This relay in operating its lower armature, closes a circuit for the lighting of lamp 104; this circuit being completed through the left hand armature and back contact of relay 105. Lamp 104 lights to indicate to the toll operator that a connection is decided over this trunk. 70 75

The toll operator answers this call in the same manner as hereinbefore described in connection with the call over trunk T and the low resistance bridge across the tip and ring conductors of trunk F causes relay 212 to 80 operate. Relay 212 in operating closes a circuit for relay 220 as follows: battery, winding of relay 220, outer left hand armature and front contact of relay 212 to ground at the armature and front contact of relay 211. Relay 220 closes the circuit for the operation of relay 218 as follows: battery, right hand winding of relay 218, armature and front contact of relay 220, left hand armature and back contact of relay 222, inner left hand armature 85 and front contact of relay 212 to ground. Relay 218 in operating provides a locking circuit for itself from battery, left hand winding and inner left hand armature and front contact of relay 218, outer left hand armature 90 and back contact of relay 223 to ground at the armature and front contact of relay 211. Relay 218 by opening the connection at its outer right hand armature and back contact removes the tone for the calling subscriber 100 supplied from the tone source 217. This relay also provides a holding circuit for relay 211 by establishing a connection to ground at its inner right armature and back contact. This is for the purpose of holding relay 211 105 operated and the preceding switch busy as long as the toll operator's cord is connected to the trunk.

The operation of relay 218 causes connections to be made for the automatic return of 110 the coin that the subscriber deposited to enable him to call. The first effect of the operation of this relay will be the operation of relay 206 over a circuit as follows: battery, winding of relay 206, outer right hand armature and back contact of relay 223, outer left hand armature and front contact of relay 218 to ground. Relay 206 in operating closes a circuit for the starter relay 228 of the circuit R which is common to a plurality of trunks 115 such as F. An ordinary step-by-step switch having contact banks 229, 230, 231 and 232, and a stepping magnet 233 are provided in this common circuit for the momentary application of a high voltage current to the 120 line for the return of the coin through the operation of coin magnet 236 at the operator's set. The circuit for starter relay 228 may be traced as follows: battery, winding of relay 228, left hand armature and back contact of 125 130

relay 236, middle lower armature and front contact of relay 206, to ground at the left hand armature and back contact of relay 237. The operation of this relay closes a circuit for the marginal relay 238 as follows: battery, armature and front contact of relay 228, armature and back contact of relay 233, winding of relay 238, left hand armature and back contact of relay 240, brush of bank 229 to ground at the inner lower armature and back contact of a relay corresponding to relay 206 of the trunk to which the brush of bank 231 happens to be connected. It should be understood that the brushes of this step-by-step switch remain on the terminals of the last trunk that employs this common equipment R. The operation of relay 238 closes an obvious circuit for the stepping magnet 233 which in operating moves the brushes of the switch to the terminals of the next trunk and also opens the circuit for the relay 238 which in releasing opens the circuit for the stepping magnet. In this manner the stepping magnet is alternately operated and released to step the brushes of the switch as long as a ground is found on the bank 229. When the brush of bank 229 connects with the terminal associated with trunk F no ground will be present on this terminal, due to the fact that the relay 206 is operated, but instead a battery connection will be associated with this terminal through the winding of relay 223. The marginal relay 238 will therefore not again be operated and consequently the stepping magnet will cease operating.

It should be noted that a connection is now established for the operation of relay 240 as the winding of this relay is connected to ground. This relay is normally short-circuited by the ground at the relays corresponding to relay 206 during the operation of the switch. The marginal relay 238 cannot operate as the resistance to ground through the winding of relay 240 is too high. Relay 240 operates in the circuit from the starting relay 228 through the armature and back contact of stepping magnet 233, winding of relay 238, the winding of relay 240 to ground. As relay 240 operates direct ground will be connected at the left hand armature and front contact of this relay for the operation of relay 223. The circuit for relay 223 may be traced as follows: battery, through the winding of relay 223, make-before-break contacts of this relay, inner lower armature and front contact of relay 206, the terminal on bank 229 of this trunk, left hand armature and front contact of relay 240 to ground. Relay 223 in operating closes a locking circuit for itself through its inner right hand armature and front contact to ground at the armature and front contact of relay 211. Relay 223 in operating opens the locking circuit for relay 218 at its outer left hand armature and back

contact. Relay 218 is however still held 65 operated through its original energizing circuit by the ground supplied at the inner left hand armature and front contact of relay 212. Relay 223 also opens the original energizing circuit for relay 206 at its outer right hand 70 armature and back contact, but it should be noted that the operation of relay 240 closes a circuit for holding relay 206 as follows: battery, winding of relay 206, terminal on bank 230 of trunk F, the brush of this bank, 75 outer right hand armature and front contact of relay 240 to ground. Relay 223 also closes at its inner left hand armature and front contact, a connection for repeating coil 214 to the trunk F for class of service tone purposes. 80 The application of class of service tone in this trunk is the same as for trunk T and need not therefore be described.

Returning now to the operation of relay 240 the first effect in the common circuit R 85 from the operation of this relay will be the closing of a circuit for relay 242, as follows: battery, winding of relay 242, make-before-break contact of this relay, middle right hand armature and front contact of relay 240 90 through the interrupter 243 to ground when a connection is established through this interrupter. Relay 242 in operating closes a locking circuit for itself through its left hand armature and front contact and the outer right hand armature and front contact of relay 240. The operation of relay 242 now establishes a circuit for the operation of relay 244 as follows: battery, through the connecting segments of interrupter 245, left hand armature and back contact of relay 246, right hand armature and front contact of relay 242, winding of relay 244 to ground. It should be noted that if the connecting segments of interrupters 243 and 245 are such that the connection through interrupter 245 is established a sufficient period after the connection established through interrupter 243 to permit the relay 242 to operate, the relay 244 will be operated by the interrupter 245 for the full 105 period of connection. This interrupter 245 may be so constructed that the circuit is open for half a second and closed for half a second alternately and relay 244 will now be operated for a half second period. When relay 244 110 operates the interrupter 245 will be connected through the outer left hand armature and back contact of this relay and the right hand armature and front contact of relay 242, through the winding of relay 244 to ground so 115 that the circuit for holding relay 244 will be dependent on the closure of its own contacts. The original energizing circuit for relay 244 just traced will be open at the left hand armature and back contact of relay 246 due to the 120 operation of this relay on the operation of relay 244. The circuit for relay 246 is as follows: battery, right hand winding of relay 125

246, middle left hand armature and front contact of relay 244 to ground. Relay 246 provides a locking circuit for itself through its inner right hand armature and front contact 5 to ground at the inner right hand armature and front contact of relay 240.

The operation of relay 244 closes a connection from battery and ground through its inner right hand and left hand armatures 10 and front contacts, through the brushes of banks 231 and 232 and the conductors of trunk F, through the upper outer and lower outer armatures and front contacts of relay 206 to the tip and ring conductors of the 15 trunk F to switch S'. It should be noted that this connection of battery and ground is a reversal of the normal connection through repeating coil 205 and relay 204. The purpose of this connection is to establish certain 20 changes through switch S' in circuits of this general type, but as these changes form no part of this invention they need not be described.

When the interrupter 245 opens the above 25 traced circuit for relay 244 this relay will release and a circuit thereby closed for the operation of relay 248 as soon as interrupter 245 again is connected to battery. This circuit may be traced as follows: battery, interrupter 30 245, outer left hand armature and back contact of relay 244, outer right hand armature and front contact of relay 246, winding of relay 248 to ground. Relay 248 will be held operated as long as the connection through 35 interrupter 245 is maintained, which may be one-half of a second. The operation of this relay will now supply current from the 110 volt supply at 250 through the left hand armatures and front contacts of this relay, 40 inner left and right hand armatures and back contacts of relay 244, brushes of banks 231 and 232, tip and ring conductors of trunk F over the connection to the calling subscriber's set for the operation of the coin magnet 234 45 to refund the coin.

The operation of relay 248 closes an obvious circuit for the operation of relay 236. A holding circuit for relay 246 through the left hand winding thereof will be established 50 by the operation of this relay. It should be noted that relay 236 in operating opens the original energizing circuit for relay 228 but as long as relay 248 is operated relay 228 will be maintained operated over a circuit as follows: battery, winding of relay 228, outer right hand armature and front contact of relay 248, to the ground at the relay 237 as hereinbefore traced. When relay 248 releases 55 at the end of the one-half second period, relay 236 will release, but due to its slow-to-release characteristics this release will not take place until after the circuit for relay 228 has been opened at the outer right hand armature and front contact of relay 248. Conse-

quently relay 228 will release during the open 65 period of its circuit and cause the release of the relay 240. Relay 240 in releasing causes the release of relay 242, while relay 236 causes the release of relay 246. This relay in releasing closes a portion of the circuit from the 70 interrupter 245 to relay 244 but as relay 242 is released at that time relay 244 cannot again operate. Consequently the interrupters 243 and 245 will have no further effect and this common circuit R is now ready for use by another trunk. The release of relay 240 also 75 opens the holding circuit for relay 206 which releases and connects the tip and ring conductors through to the repeating coil 205.

This trunk is also, as hereinbefore mentioned, arranged to pass the class of service tone to the toll operator in the same manner as trunk T. The class of service tone may also be removed from the trunk by the toll operator, by the operation of key 111. 80

A connection between the calling subscriber and the toll operator is now completed with the talking battery and ground supplied for the calling subscriber through the winding of relay 204 and the ground at the repeating 90 coil 205. The calling subscriber may give the number of the wanted subscriber to the toll operator and the toll operator may establish a connection to the subscriber in the usual manner. Conversation between the 95 calling subscriber and the called subscriber may therefore begin as soon as the calling subscriber has deposited the proper amount of coins required for the call.

The toll operator instructs the calling subscriber to deposit this amount and arrangements are made for refunding or collecting the deposited coins in this circuit in the same manner as described in connection with circuit T. Supervision of the circuit may be 100 had in the same manner as described in connection with trunk T and the release of the connection after conversation ceases may also be made in the same manner as described in 105 connection with trunk T.

It should be understood that while this invention has been described in connection with a trunking system in which the trunk may be seized through the medium of automatic switches and it has been assumed that the 115 subscriber will not be able to dial until a coin has been deposited, the invention is not limited to systems of this kind, but may be equally well applied to other systems, for example, where the coin is deposited after the trunk 120 has been seized, without departing from the spirit of the invention.

What is claimed is:

1. In a telephone system, a subscriber's line, a coin collect and refund device associated therewith, a trunk, means for connecting said line and device to said trunk at one end thereof, an operator's cord for associa-

- tion with said trunk at the opposite end thereof, means responsive to the actuation of said first means and the association of the cord with the trunk for actuating said device 5 to refund a coin deposited therein.
2. In a telephone system, a subscriber's line, a coin collect and refund device associated therewith, a trunk, means for connecting said line and device to said trunk, at 10 one end thereof, an operator's cord for association with said trunk at the opposite end thereof, a source of current, means responsive to the actuation of said first means and the association of the cord with the trunk for 15 applying current from said source over said line to said device to actuate it to refund a coin deposited therein.
3. In a telephone system, a subscriber's line, a coin collect and refund device associated therewith, a trunk, means for connecting said subscriber's line and device to said trunk at one end thereof, an operator's cord for association with the other end of said trunk, a source of current, and means responsive 20 to the connection of said line and cord to said trunk for applying current from said source to said device for a definite period of time to actuate said device to refund a coin deposited therein.
4. In a telephone system, a subscriber's line, a coin collect and refund device associated therewith, a trunk, means for connecting said subscriber's line and device to said trunk at one end thereof, an operator's cord 25 for association with the other end of said trunk, a source of current, an interrupter, and means responsive to the actuation of said means and the association of the cord with the trunk for applying current from said source to said device under control of said interrupter to actuate said device to refund a coin deposited therein.
5. In a telephone system, a subscriber's line, a coin collect and refund device associated therewith, a trunk, means for connecting said line and device to said trunk at one end thereof, an operator's cord for association with said trunk at the opposite end thereof, a direct current source, a circuit 30 interrupter, a circuit and relay arrangement controllable by said interrupter, means responsive to the actuation of said first means and the association of the cord with the trunk for placing the circuit and relay arrangement under control of said interrupter to apply current from said source over said line to said device for operating it for a period equal to one circuit closure of said interrupter to refund a coin deposited in said device.
6. In a telephone system, a subscriber's line, a coin collect and refund device associated therewith, a plurality of trunks, means for connecting said line and device to any one of said trunks at one end thereof, an operator's cord for association with any one of said trunks at the opposite end thereof, and means common to all of said trunks responsive to the connection of a trunk to said line and said cord for actuating said device to refund a coin deposited therein.
7. In a telephone system, a subscriber's line, a coin collect and refund device associated therewith, a plurality of trunks, means for connecting said line and device to any one of said trunks at one end thereof, an operator's cord for association with any one of said trunks at the opposite end thereof, a source of current, a switching means, and means for actuating said switching means responsive to the connection of a trunk to said line and said cord for applying current from said source over said trunk and line to said device to actuate it to refund a coin deposited therein.
8. In a telephone system, a subscriber's line, a coin collect and refund device associated therewith, a trunk, means for connecting said line and device to said trunk, an operator's cord for association with said trunk, and means responsive to the actuation 50 of said first means and the association of the cord with the trunk for actuating said device to refund a coin deposited therein.
9. In a telephone system, a telephone line, a coin collect and refund device associated with said line, a trunk, means for connecting said line to said trunk, an operator's cord for making connection with said trunk, a source of current, and means responsive to the actuation of said first means and to the connection of the cord with said trunk for applying current from said source over said line to actuate said device to refund a coin deposited therein.
- In witness whereof, I hereunto subscribe my name this 24th day of October A. D., 1927.
- RALPH L. QUASS.
